UNITED STATES PATENT OFFICE.

GUST N. CARLSON, OF OTTUMWA, IOWA.

CLINKER TONGS.

Application filed June 30, 1923. Serial No. 648,777.

To all whom it may concern:

Be it known that I, GUST N. CARLSON, a citizen of the United States, residing at Ottumwa, in the county of Wapello, and State of Iowa, have invented certain new and useful Improvements in Clinker Tongs, of which the following is a specification.

This invention relates to clinker tongs, and particularly, to a construction of the jaws thereof, whereby they are adapted to grasp large or small pieces of material and thus designed for use either through the main feeding opening or through a smaller clinker door.

14. In ordinary constructions of such tongs, the jaws are bulky and occupy considerable space when introduced into a fire box and are not practically adapted to grasp and firmly hold small pieces of material such as slate, nor to be used as a poker for insertion in the fire bed to loosen and expose clinkers for removal when they usually form adjacent the grate bars.

26. The present invention, therefore, provides a novel improved construction whereby the jaws, when fully opened are adapted to grasp large clinkers or other pieces of material and have formed thereon parallel gripping faces, particularly adapted to engage small or flat material, these faces being of such form that they may be readily introduced into the fuel or through a small opening in the furnace.

35. A further object of the invention is to provide a novel form of the gripping jaws by which the material may be firmly held and these comprise one jaw of curved outline and angular cross section cooperating with an opposite flat jaw having gripping lugs upon its inner face.

45. Another object of the invention is to provide a tong construction having a fixed jaw and handle member and a cooperating pivoted jaw of lever type, from which a slidingly mounted handle extends, the handles of the opposite jaws being crossed so that the jaws may be held in open position by one hand of the operator and the other hand

effectively used to introduce the jaws into the fuel bed.

50. Other and further objects of the invention will be hereinafter set forth and the novel features thereof defined by the appended claims.

55. In the drawing:

Figure 1 is a side elevation of the invention;

Figure 2 is a similar view of a modified form thereof;

Figure 3 is a detail plan of the jaw shown in Figure 1;

Figure 4 is an enlarged section, thereof upon line 4-4 of Figure 1; and

Figure 5 is a plan of the flat jaw.

Like numerals refer to like parts throughout the several figures of the drawing.

The invention comprises essentially a fixed jaw and handle and a cooperating pivoted jaw, having a sliding handle. In the embodiment thereof shown in Figure 1, the numeral 10 designates the body of the fixed jaw member, which has an outwardly bent or bowed portion 11 and terminates in the gripping member 12. The opposite end of the portion 10 is deflected laterally as at 13 and provided with any desired form of hand hold, for instance the looped portion 14. Upon the member 10 the movable jaw

15 is pivotally mounted as at 16 and the lever end 17 thereof connected by the pivot 18 with the sliding handle 19. This handle has an angularly bent portion 20 crossing or intersecting the line of the portion 13 and terminates in a looped hand hold 21. For the purpose of properly supporting and guiding the handle 19 a supporting guide 22 is secured to the member 10 as at 23 and provided with an eye 24 through which the handle 19 slides. It is also desirable to normally retain the jaws in closed position and this may be accomplished by any proper arrangement of spring upon the movable jaw handle, such for instance as shown where the spring 25 surrounds the handle member and bears at one end against the eye 24 and at

85 its opposite end against a stop 26.

100

The jaws 11 and 15 are especially designed for the purpose of grasping either large pieces of material or small flat material, such as slate or other unburned objects which it is desired to remove from the fire bed. The jaw 15 is therefore formed with a bowed portion 27 opposite the portion 11 of the jaw 10 and terminates in a concentric or circular gripping face 28 having comparatively broad area and being disposed opposite the gripping face 12 of the fixed jaw. This circular portion 28 is also formed of angular cross sections, as clearly shown at 29 in Figure 4, so that it presents a sharp contacting edge to the material to be lifted.

In order to cooperate with the circular gripping portion, the gripping face 12 is provided with tapering lugs 30 and 31, the former extending longitudinally of the face 12 and opposite one of the angular faces 29, while the lug 31 is disposed beneath the circular gripping face at its point of connection with the jaw member.

In the modified form of the invention shown in Figure 2, the general construction and arrangement of parts is similar to that before described, with the exception that the fixed jaw 32 carries a circular gripping face 33 and is provided with a hand hold 34 while the movable jaw member 35 is provided with a gripping face 36 similar to the fixed face 12 shown in Figure 1. The jaw 35 is pivoted at 37 to the fixed jaw and connected to a sliding handle 38 by a pivot 39. The jaws are normally held in closed position by a spring 40 and the movable jaw provided with a hand hold 41 so that a similar action of the parts is secured to that before described, with the exception of the reverse position of the gripping faces.

The operation of the invention will be apparent from the foregoing description and it will be seen that when the jaws are in closed position the parallel gripping faces form a comparatively thin tapering end which can be readily introduced into the fire bed and used in a poker action for loosening or raising into accessible positions clinkers which may adhere adjacent the grate bars. These parallel gripping faces also provide means by which a thin or flat object or piece of material may be grasped and when fully opened the bowed portion of the jaws provides space to receive a large clinker or other object which it may be desired to remove from the fire bed.

It will also be noted that when it is desired to hold the jaws in open position as indicated by dotted lines in Figure 1, the handle may be slid into proper position for that purpose and one hand of the operator grasping the crossed portion of the fixed jaw and the hand hold of the sliding jaw is sufficient to manipulate the tool, leaving the other

hand free for applying pressure in its action as a poker or as a lifting bar for removing material from the fire bed.

The surface of the gripping faces is particularly designed to secure a firm contact upon the flat or smooth surfaces so that the action of the tong is not confined merely to that of an encircling hook.

While the specific details of the invention have been shown and described, it will be understood that changes and alterations may be made therein without departing from the spirit of the invention as defined by the following claims.

Having thus described my invention, what I claim as new and desire to secure by Letters Patent is:—

1. In a tong device, a relatively fixed jaw having a laterally deflected handle portion, a cooperating movable jaw pivoted thereon intermediate its ends, and a sliding handle portion pivoted to one end of the movable jaw and deflected laterally at its free end, said deflected portions being crossed to provide a bracing face for one hand of the operator when holding the jaws in open position.

2. In a tong device, a relatively fixed jaw having a handle portion and a bowed portion terminating in a flat gripping face, an opposite movable jaw pivoted upon said handle portion and having a bowed portion terminating in a flat gripping portion substantially parallel to the first mentioned gripping face, and a handle member extending from said movable jaw.

3. In a tong device, a relatively fixed jaw having a handle portion and a bowed portion terminating in a gripping face, an opposite movable jaw pivoted upon said handle portion and having a bowed face terminating in a gripping portion substantially parallel to the first mentioned gripping portion, a handle member extending from said movable jaw, a support carried by the fixed handle member and provided with a guide for the movable handle, a spring surrounding said movable handle and bearing against said support, and an abutment upon the movable handle for one end of said spring.

4. In a tong device, a fixed jaw member, and a cooperating movable jaw member, one of said members having a gripping face of circular configuration and the opposite member having a straight gripping face extended diametrically of the circular face.

5. In a tong device, relatively movable jaw members, one thereof having a substantially circular gripping face of angular cross section, and the cooperating member having a flat face provided with gripping lugs disposed to cooperate with the angular edge of the circular face.

6. In a tong device, a fixed jaw member

provided with a hand hold at one end and a bowed and flat gripping face at its opposite end, a cooperating jaw pivoted upon the first mentioned jaw member and provided with a bowed portion and a gripping face adapted to lie substantially parallel to the cooperating face upon the fixed jaw, and a sliding handle pivotally connected to said movable jaw, the body portions of said handles being deflected in opposite directions in ¹⁰ planes intersecting each other.

In testimony whereof I affix my signature.

GUST N. CARLSON.
